M. L. WARSING

DUST CATCHER AND SPARK ARRESTER

Filed Nov. 1, 1923

FIG. 1

Inventor
M.L.Warsing

By *A. Murphy Jr.* Attorney

UNITED STATES PATENT OFFICE.

MARTIN L. WARSING, OF ALTOONA, PENNSYLVANIA.

DUST CATCHER AND SPARK ARRESTER.

Application filed November 1, 1923. Serial No. 672,219.

To all whom it may concern:

Be it known that I, MARTIN L. WARSING, a citizen of the United States, residing at Altoona, in the county of Blair and State of Pennsylvania, have invented certain new and useful Improvements in Dust Catchers and Spark Arresters; and I do hereby declare the following to be a full, clear, and exact description of the invention, such as will enable others skilled in the art to which it appertains to make and use the same.

The object of the present invention is the provision of a device to be placed in the hot air pipes of pipeless and pipe furnaces to catch dust floating in the air and arrest dirt or other particles contained in the air whereby to supply pure hot air for heating and obviate taking dust into the lungs when breathing or having dust settle upon furnishings, draperies and walls.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a top plan view of a device embodying the invention,

Figure 2 is a side view,

Figure 3 is a section taken on the line 3—3 of Figure 1, and

Figure 4 is a section taken on the line 4—4 of Figure 1.

Corresponding and like parts are referred to in the following description and designated in the several views of the drawings by like reference characters.

The device comprises a frame, a plurality of bars carried by the frame and disposed in spaced relation, and fluffy material carried by the bars and operating to remove dust from the air and sparks from smoke and products of combustion.

The frame in its specific formation, is constructed of wire of suitable gage which is bent to provide opposed reversely inclined or helical elements 1 and tie elements 2 connecting the helical elements, said tie elements having an approximate parallel rela-

tion and disposed substantially perpendicular to the helical elements 1. The ends of the wire comprising the frame terminate in eyes which are interlooped, as indicated at 3. Diametrical bars 4 have a spiral or helical arrangement and are connected at their ends to the helical elements 1 at diametrically opposite points. The bars 4 cross upon an axial line and are regularly spaced at their outer ends. In the preferable construction, each of the bars 4 is of channel formation, the opening being constricted at the outer side, whereby to retain the fluffy material 5 pressed into the space formed between the side walls of the bar. Ears at 6 opposite ends of the bars are bent about the helical elements 1, as indicated at 6, and the bars are maintained in predetermined spaced relation by means of sleeves 7 mounted upon the elements 1. The bars in cross section are of wedge form and the material 5 is pressed into the space formed between the side walls or flanges and may consist of asbestos, mineral wool or the like which is fluffed or frayed to catch dust in the air and arrest sparks contained in the smoke or products of combustion.

The device is designed to be located in the hot air pipes of hot air heaters, such as pipe and pipeless furnaces, and operates to remove dust and other particles from the air so that the latter is filtered and supplied for heating free from dust, dirt and any other objectionable particles.

What is claimed is:

1. A device of the character specified, comprising a plurality of channel bars disposed in spaced relation, and material confined in the space of the bars and having portions projecting and fluffed to catch dust in the air and arrest sparks contained in smoke and products of combustion.

2. A device of the character specified, comprising a frame including opposed reversely inclined elements, and tie members connecting said elements and arranged in parallel and diametrical relation, channel bars disposed in helical and diametrical relation and connected at their ends to said inclined elements at diametrically opposite points, and material disposed in the spaces of the bars and having portions projecting and fluffed to catch dust in the air and arrest sparks contained in smoke and products of combustion.

3. A device of the character specified, comprising opposed arcuate elements reversely inclined, tie members connecting the ends of the elements, diametrical bars disposed in spaced relation and connected at opposite ends to the inclined elements at diametrically opposite points, and material

carried by said bars to catch dust in the air.

In testimony whereof I affix my signature in presence of two witnesses.

MARTIN L. WARSING.

Witnesses:

ALEX. WEIR,
JOHN H. GOSSARD.
